UNITED STATES PATENT OFFICE

AURÈLE VERMEULEN, OF LOS ANGELES, CALIFORNIA

STRUCTURAL DEVICE

Application filed March 13, 1931. Serial No. 522,280.

This invention relates to structural devices, and particularly to devices which may constitute built-up units for the purpose of constructing platforms, bridges, ferries, ships, piers, pontoons, floats, buoys, and other floating constructions as well as for foundations, walls, piers, columns, bulkheads, and the like.

The invention has for an object the provision of a novel and economic system and means of construction whereby units may be additively joined together to produce a floating, submerged, or exposed structure and in accordance with the requirements of said structure.

Another object is the provision of means of building construction which may be conveniently assembled.

Another object is the provision of building construction means which is adaptable for many uses and purposes and may, in certain embodiments, act in conjunction with other building construction units for strengthening the same.

Other objects of the invention will appear as the specification proceeds, among which is the provision of units for building construction which are simple as to structural detail, economical in use and service, may be easily interlocked for joint operation, and which may be embodied in many forms within the scope of the invention.

With the above and other objects in view, the invention consists in the novel and useful provision, formation, construction, association and relative arrangement of parts, members and features, all as shown in certain embodiments in the accompanying drawings, described generally, and more particularly pointed out in the claims.

In the drawings:

Figure 1 is a perspective view of a floating platform embodying one form of the invention,

Figure 2 is a fragmentary plan view of the floating platform shown in Figure 1 and showing certain features of its construction,

Figure 3 is a sectional view on the line 3—3 of Figure 2,

Figure 4 is a sectional view on the line 4—4 of Figure 2,

Figure 5 is a sectional view on the line 5—5 of Figure 2,

Figure 6 is a sectional view on the line 6—6 of Figure 2,

Figure 7 is a perspective view of a float embodying further details of the invention,

Figure 8 is a plan view of the float of Figure 7,

Figure 9 is a side elevation of the float shown in Figure 8,

Figure 10 is a plan view of a further detail of the invention which may be utilized as a float,

Figure 11 is a sectional view on the line 11—11 of Figure 10,

Figure 12 is a fragmentary perspective view of a locking member for that form of the invention shown in Figure 10,

Figure 13 is a fragmentary side elevation of a floating type of platform which may embody the invention,

Figure 14 is a fragmentary plan view of the floating platform shown in Figure 13,

Figure 15 is a transverse sectional view of a further form of the invention,

Figure 16 is a sectional view on the line 16—16 of Figure 15, and,

Figure 17 is a fragmentary transverse sectional view showing certain details of the interlock of that form of the invention shown in Figures 15 and 16.

Corresponding parts in all the figures are designated by the same reference characters.

Referring now with particularity to the drawings and for convenience, I shall designate certain forms of my invention by capital letters, to-wit: that form shown in Figures 1 to 6 by A; the form shown in Figures 7, 8 and 9 by B; Figures 10 and 11 by C; Figures 13 and 14 by D; and 15, 16 and 17 by E, and such forms will be taken up in alphabetical order.

For convenience of illustration, the form of the invention A has been shown as a floating platform, although within the purview of the invention, I may utilize the invention

for various further purposes. Thus, in the present instance, the invention A may form a float situated in the ocean and which float is free to rise and fall and may be utilized 5 for various purposes, such as a landing platform for airplanes, and other air vehicles, lighthouses, buildings, etc. It is not to be considered that the form of the invention, shown in Figure 1 should necessarily be confined to a given size, as it is intended that 10 many units be utilized and a comparatively broad expanse may result.

In the form A, I have shown a plurality of interconnected units *a*. These interconnected units may be made of any material best suited to the purposes intended, for instance, concrete. In forming these units, however, it is important that the units and each thereof be so molded as to provide a 20 chamber 1. This chamber may extend longitudinally of the units *a*, as indicated by the dotted lines in Figure 2 at 2. In the embodiment of the invention shown, this chamber is practically an enclosed one. However, a metal piece 3 may be placed within 25 an opening transversely extending between an outer surface of said unit and the chamber 1 and which member 3 is screw-threaded at 4 for reception of a plug nut 5. Thus, by 30 removing the plug nut, entrance may be had within the chamber. What may be termed the top surface of a unit *a*, to-wit, the surface 6, is provided with one or more spaced apart dove-tailed type transverse 35 grooves 7; also one of the side walls 8 is provided with one or more transversely extending dove-tailed tongues 9. The opposite surface 10 is formed with one or more transversely extending dove-tailed slots 11. 40 Certain of the units *a* may be provided with one or more transverse bores 12. The arrangement of the various units is now apparent. The several units may be interconnected by the tongues 9 of one unit being received within the slots 10 of its contiguous 45 unit *a*, and so on. After this assemblage, a reenforced locking member 13 may be received within the dove-tailed grooves 7 of all said units. This construction will aid in 50 maintaining the surface of said units in alignment. This reenforced locking member may be conveniently formed by making it of the same material as the units *a*, such as concrete, within which appears metal wire 55 reenforcements such as shown at 14 in Figure 3. Hence, the member 13 may be either constructed prior to joining the units, or the construction may be a poured one by laying the metal wire reenforcements within the 60 dove-tailed slots 7 and bridging said slots in each contiguous unit, of course, properly spacing said reenforcements, followed by pouring of concrete or other plastic substance within said dove-tailed slots so as to 65 embed the reenforcements. This, of course,

will provide for a connected surface aligning structure comprising a plurality of interconnected units.

For shore anchorage purposes, I may provide tubes, poles or posts 15 which are 70 adapted to be passed through the transverse openings 12. A plurality of these posts are provided, as shown in Figure 1, and aid in maintaining the platform in a given position. The platform may rise and fall with 75 the ebb and flow of the tide.

It will be realized that where the units are utilized as a float that the chamber 1 is not filled but is sealed against entrance of water therein. If, however, the units are 80 to be utilized for ballast purposes, the chambers may be filled with fluid, such as water or sand, as shown at 16, by removing the cap nut 5.

In the form of the invention just described, it is also to be noted that the tongue 9 of each unit as well as the groove 11 are tapered in form from the top surface of each unit to the bottom thereof, as best shown in Figure 6 at 17. This construction 90 aids in the interlock that exists between contiguous units and practically assures that said units do not become separated but are maintained in horizontal alignment when the locking member 13 is in position and 95 joining said units.

The invention A may be submerged by filling the chambers, and to this end the chambers would act as ballast chambers.

Referring to the form of the invention B, 100 it will be seen that this form does not differ in essential details from the form A or for that matter from the remaining forms of the invention. As before, the invention B is made up of one or more units *b* which are 105 adapted to be interconnected and so held. Each unit *b* having four side portions is adapted to have one or more of said side portions provided with tapered dove-tailed slots 18 as, for instance, the sides 19 and 20, 110 while the sides 21 and 22 may be provided with outstanding tapered transversely extending tongues 23. Obviously, if the several units *b* are identically constructed, the 115 tongues of one unit will fit within the dove-tailed slots of a contiguous unit, as shown in the figures. Each unit *b* is provided with an internal chamber 24, access to which may be had through the plug 25. The slots 18 as well as the tongues may likewise be 120 tapered as to transverse width. This construction is indicated at 26 in Figure 9.

This invention B may have its units joined and may act as a float if the chambers are air filled and held to a pier or the like, through the medium of chains 27 or the like. The float is, of course, more enduring than the ordinary wood type of float, due to its construction, which is preferably formed of concrete. Obviously the molding or form- 130

ing of the units either *a* or *b* is no factor, as they may be formed in many ways, such as by molding or the like. For instance, an outer mold and an inner mold are provided, 5 with the concrete poured therebetween so as to have a base and side walls, whereupon a thin piece of material may be placed across the side walls sufficient to cover or close one end of the chamber, whereupon concrete 10 may be poured upon this member to form the other end and the concrete allowed to harden in the mold. This is one method that may be utilized.

The form of the invention C utilizes constructional units *c*, *d*, *e* and *f*. The units *c* are six-sided although it is evident that the number of sides does not make any difference. The units *e* are four-sided or one-half the size of a unit *c*. The units *d* and *f* 20 are triangular in form. All of the said units are so cast as to provide an internal elongated chamber 28 and, furthermore, said units are formed with elongated dove-tailed grooves 29, substantially one groove for 25 each side. As before, access to the chamber 28 may be had through a plug 30. In addition, the dove-tailed groove 29 progressively varies in transverse width on the top surface 30 of each unit to the base thereof. After a given number of irregular units are joined together in any configuration desired and so as to provide a side wall of defined form, for instance, the form shown in Figure 10, 35 said units may be interlocked through the medium of the key shown in Figure 12. It will be seen that this key is transversely tapered and that opposite sides 31 and 32 are given a V-shaped groove. If this tapered 40 key was split centrally of the V-shaped groove, then a dove-tailed key would result. Thus, this key construction acts to bridge 45 between two slots in the units and hold said units in cooperative relation, as shown in Figure 10.

Certain of the units may be provided with outstanding eyes 33, whereby a rope or the like 34 may encircle the several units *d*, *e* and *f* and maintained in encircling position 50 by being passed through said eyes 33. It will be seen also in Figure 10 that one of the units *c* is provided with an integrally formed key 35. This is shown by way of illustration. Thus, the forms *d*, *e* and *f* 55 may be provided with integrally formed keys in place of providing the key shown in Figure 12.

The form of the invention D may utilize units of the type shown in Figures 1 to 6, 60 that is to say, said units here designated as *g* may or may not be provided with a surface groove of the form 7 but said units are provided with dove-tailed type tongues and slots 36 and 37, respectively whereby contiguous units may be interlocked. Thus, several

units may be arranged in pyramid form, as shown in Figure 13, and when so arranged may support a platform, such as illustrated at 38. All units *g* are provided with a chamber the same as for the units *a*. 70

The form E includes units *h* adapted to be interlocked. Each unit *h* is provided with a chamber 39. When the units are being formed, they have molded within the wall one or more encircling wires 40. At 75 each corner of the unit, the wire extends outwardly in the form of a loop, as shown at 41, and the unit at each one of the corners is curved or cut away, as shown at 42. When it is desired to join contiguous units, the loops 41 of each contiguous unit are so arranged that they overlie as best shown in Figure 16 at 43, and in which figure several of said loops are utilized. The arrangement is such, when several units are joined, that a way 44 is provided. If there are four units, the way 44 is substantially circular, and if two units, semi-circular. Within this way and through the eyes of said loops may be passed a rod, or concrete may be poured within said way and through the loops of the wires which will lock the wires together and likewise the contiguous units. 90

It will be seen that I have provided structural units which are adaptable for many purposes, and may form the foundation for other units of building construction. This invention may be utilized with its units either submerged or exposed to provide foundations, walls, bulkheads, and the like, as was pointed out in the objects of the invention. The invention consists, in its broadest aspect, of a unit having a chamber with means for interlocking the unit and means for access to the chamber, whereby the chamber may be filled with a ballasting material, if desired. This means for interlocking the various units may constitute a separate key or a key integrally formed on the unit for reception in a corresponding locking portion of an adjacent unit. Furthermore, the method of aligning the various units is thought to be novel. 105

It is obvious that various changes and modifications and variations may be made in practicing the invention in departure from its several forms, as illustrated in the drawings, without, however, departing from the true spirit of the invention. 115

I claim:

1. In a device of the character disclosed, a block, the upright corner edges of which are grooved, loop members secured to and extended in part outwardly from the grooves of said corners and whereby when said loop members are aligned with corresponding loop members of an adjoining block, said loop members may be interlocked in said grooves, the blocks being held in close abutting relationship, and means adapted to be 125

passed through said loop members and within said grooves for interlocking the blocks.

2. In a device of the character disclosed, a block formed with a central chamber portion, corner portions of said block being grooved, and a wire encircling said block and embedded therein, said wire being provided with loop portions extending outwardly from the periphery of said block at adjacent grooved corner portions.

In testimony whereof, I have signed my name to this specification at Los Angeles, California, this 12th day of February, 1931.
